BELT-SUPPORTED GOLF BALL CARRIER

Verne N. Price, 2048 Petaluma Ave., Long Beach, Calif.,
assignor of one-half to Dave Davis, Long Beach, Calif.

Filed June 23, 1964, Ser. No. 80,538

Term of patent 14 years

(Cl. D34—5)

FIG.1

I claim:

The ornamental design for a belt-supported golf ball carrier, substantially as shown.
